CESARE CAMPUS, OF NEW YORK, N. Y.

MATCH-BOOK.

1,125,647.

Specification of Letters Patent.

Patented Jan. 19, 1915.

Application filed November 29, 1912. Serial No. 734,080.

To all whom it may concern:

Be it known that I, CESARE CAMPUS, a subject of the King of Italy, and a resident of the city of New York, borough of Manhattan, in the county and State of New York, have invented a new and Improved Match-Book, of which the following is a full, clear, and exact description.

This invention relates generally to match books, and is particularly directed to an improved construction affording many advantages, the principal of which are as follows:—to provide a match book with a plurality of covers so that the heads of the matches, when the book passes through the machine, will be substantially protected from injury; to provide a match book comprising a plurality of covers whereby, when the same is carried in the pocket for any length of time, the outer cover, which may be soiled, may be removed, thereby exposing the next cover, which is substantially clean; to provide a match book comprising a number of covers or leaves which will offer a medium for taking down notes or records, such as telephone numbers or street addresses; and, finally, to provide, if so desired, a scratching surface on the outside of the inner cover so that when the covers are closed the said scratching surface will be protected from moisture and injury.

Many other advantages follow the use of the match book described and claimed, which will appear as the description thereof proceeds.

Reference is to be had to the accompanying drawings forming a part of this specification, in which like characters of reference indicate corresponding parts in all the views, and in which—

Figure 1 is a perspective view of the preferred form of the match book; Fig. 2 is an end view thereof; while Fig. 3 is a perspective view of the modified form.

The structure comprises the cards 1 carrying the usual safety matches 2 held in position between the covers 3—4 in any suitable manner, as by bending the end portions 5 of the covers around the said cards, the parts being maintained in position in any suitable manner, as by stitching 6. The particular size and shape of the covers 3—4 are immaterial as far as the inventive idea is concerned; however, each of the covers is cut from a roll containing a number of them, the said roll of material being provided ad-

jacent its edges with openings 7, so that when the material passing from two rolls are placed one above the other in being brought into the machine for fixing the 60 covers to the card, a suitable mechanism will engage in the registering openings 7, thereby providing for proper positioning of the two covers relatively to each other. The production of covers or leaves in the form 65 of a roll provided with the apertures or openings 7 as a medium for insuring the proper relation thereof to each other, presents a decided improvement in this art, and especially over those methods of binding the 70 books, wherein the two covers are assembled, being provided in their cut form.

The material which comprises the striking heads of the matches 2 is brittle; the passage of the book through the machine in 75 which the covers are secured thereto brings pressure to bear on the matches, especially on the heads, so that it very often happens that such books are rendered unfit for use because of the injury to the said brittle 80 head. It is possible to overcome such liability of damage by using a single cover of much thicker material than is at present used, but I have found, however, that the use of a number of covers of relatively small 85 thickness offers the same protection to the heads of the matches as the relatively thicker material; in fact, because of the presence of air between the covers a cushion is provided so that the heads of the matches 90 are substantially prevented from injury during the operation mentioned.

The scratching surface 8 may be mounted at one end of the outer cover 3, as shown in Fig. 1; referring particularly to Fig. 3, it 95 will be noted that this scratching surface 8 is provided adjacent one end of the inner cover 4', being brought adjacent the stitched end of the outer cover 3 when the parts are lapped or held together, as shown in this 100 figure.

The particular advantage of so positioning the scratching surface is this:—The danger of ignition of all of the matches in the book when one of them is struck on the 105 striking surface is lessened, due to the fact that the inner cover 4' will be brought into some position to cover the matches 2 before the striking surface can be used. This particular location of the striking surface 8 110 also permits the outer cover 3, when brought into closed position, to protect the said

scratching surface from moisture or injury, and also to avoid the liability of other articles in the pocket coming in contact with the material of the said scratching surface.

5 With either form of the match book the inventive idea is essentially the same; these match cards or books are generally carried about in the pocket and become more or less soiled, and it very often happens that the 10 outer cover loses its shape, whereby it can no longer be closed; in such event the outer cover may be simply torn off, leaving the inner cover, which presents a neat appearance and at the same time protects the 15 matches.

As previously stated, the plurality of covers offer a very convenient means of carrying memoranda, such as telephone numbers or addresses, as it frequently happens that 20 such data must be taken down with little forewarning, as during a telephone conversation.

Having thus described my invention, what I claim as new and desire to secure by Letters Patent is:—

25 1. A match book comprising a match card, a plurality of superposed covers substantially coextensive and mutually reinforcing each other when in closed position, one end 30 of each of the covers being secured to the lower end of the card, the outer free ends of the covers being clamped between the card and the secured ends of the covers, when in closed position, and a scratching surface 35 mounted upon the inner cover on the exterior surface thereof, whereby the inner cover may be closed to afford a protection to the head of the matches when the scratching surface is being used.

40 2. A book as characterized, comprising a match card having a stub section; a cover for said card embodying a plurality of coextensive separable relatively resilient sheets, the said sheets at one end of said cover being 45 disconnected to spread apart, said cover being wrapped about said stub; and means for

rigidly uniting said stub and the wrapped ends of said cover on a line removed from the edge of said wrapped portion of said cover.

50 3. A match book, comprising a match card having a stub section; an inner cover for said card adapted to encompass the same and having an abrasive section formed on the outer surface of said cover adjacent the free end thereof; and an outer cover coextensive with and overlying said inner cover.

55 4. As an article of manufacture, a match book comprising a match card having a stub section; a cover to encompass said card, said cover embodying a plurality of relatively thin, coextensive, separable strips; and means for fastening said cover and the strips thereof to said stub, leaving the end edge of the fastened portion of said cover free to 60 separate from said card, to permit the insertion therebetween of the free end of said cover.

65 5. As an article of manufacture, a match book comprising a match card and a laminated cover for said card to encompass the same, said cover embodying a plurality of relatively thin, resilient strips adapted individually to bend at a sharp angle, and collectively to protect said card.

70 75 6. As an article of manufacture, a match book comprising a match card; a cover therefor embodying a plurality of overlaid, coextensive, relatively thin, separable strips, said strips being adapted individually to 80 form a narrow fold, and collectively to provide an augmented display surface and a protection for said card; and means for attaching said cover to said card in service relation thereto.

85 In testimony whereof I have signed my name to this specification in the presence of two subscribing witnesses.
